AUTOMATIC MINE CAR COUPLING

Charles Conway Montgomery and Walter Ernest Chelgren, Hardburly, Ky.

Application April 18, 1936, Serial No. 75,206

1 Claim. (Cl. 213—175)

This invention relates to couplings for mine cars, and has for the primary object the provision of a device of this character which will automatically couple cars to provide a saver of time and labor and which will readily adjust itself when coupling cars on uneven tracks and when operating on curves in the track.

With these and other objects in view, this invention consists in certain novel features of construction, combination and arrangement of parts to be hereinafter more fully described and claimed.

For a complete understanding of our invention, reference is to be had to the following description and accompanying drawings, in which

Figure 1 is a fragmentary side elevation illustrating a car coupling adapted to adjacent ends of cars and constructed in accordance with our invention.

Figure 2 is a fragmentary top plan view illustrating the same.

Figure 3 is a sectional view taken on the line 3—3 of Figure 2.

Figure 4 is a sectional view taken on the line 25 4—4 of Figure 3.

Figure 5 is a perspective view illustrating the male element of the coupler.

Referring in detail to the drawings, the numeral 1 indicates a male element of the coupler which is in the form of a bar and has one end bent to form a hook 2 adapted to enter the female element 3 of the coupler. The male element has an opening 4 to receive a king pin 5 of a draw bar 6 of a car. Engaging with opposite sides of the 35 pivoted end of the male element are spring members 7 acting to keep the male element centered and which will permit said male element to have a limited pivotal movement so that the hook-shaped end will readily enter the female element 40 when in the act of coupling.

The female element is suitably secured to a second car and is in the form of a housing 8 provided with a chamber 9 therein and which opens outwardly through one end of the housing to form 45 a mouth 10. The mouth is of flared formation, as clearly shown in Figures 3 and 4. Between the mouth 10 and the chamber is a throat 11 and communicating with the throat is a recess 12 formed in one of the walls of the housing. The 50 throat where merging into the chamber 9 defines spaced shoulders 13 each having a recess 13'. A shaft 14 is journaled in the housing and traverses the recess 12 above the throat and has se-

cured thereto a dog 15 which may move into and out of the throat from the recess 12. When the dog occupies a position in the throat the opposite extending lugs 16 thereof contact the shoulders 13 and thereby relieve the shaft of strain and such strain is placed thereon by the hook 2 of the male element being in engagement with said dog and the second car pulling the first car. The shoulders 13 have recesses 13' in which the lugs 16 may move and thereby limit the downward 10 pivotal movement of the dog.

An arm 17 is secured to one end of the shaft 14 and has connected thereto a coil spring 18. The spring 18 is secured to the second car and acts to urge the dog into the throat from the recess 12 15 so that in order to move the dog into the recess 12 from the throat the arm 17 must be raised. In order to raise the arm 17 an operating lever 19 is connected to the arm 17 by a flexible element 20 and is pivoted to the second car, as 20 shown at 21. A pull downwardly on the free end of the operating lever will elevate the lever or arm 17 and move the dog from the throat into the recess 12. The dog occupying a position within the recess 12 will be free of the hook-shaped end 25 of the male element of the coupler so that the cars may pull apart when moved relative to each other. The free end of the operating lever may be latched in a downward position by engaging a catch 22 thereof with teeth 23 of a rack 24. 30

Cars equipped with a coupler of the character described will become automatically coupled together when moved towards each other due to the male element entering the female element and the dog becoming engaged with the hook 2. 35 Should the cars be operating on a curve, the flared mouth 10 will readily guide the male element into the throat of the female element to become engaged by the dog.

Having described the invention, we claim: 40

A coupler comprising a housing having a flared mouth and a chamber communicating with said mouth by a restricted throat defining spaced shoulders located in said chamber and each having a recess, a dog pivoted in the housing and having pivotal movement in the throat and chamber to engage a male element, oppositely extending lugs carried by the dog to ride said shoulders and engage in the recesses thereof during the engagement of said dog with the male element, 45 and an operating means for the dog.
